UNITED STATES PATENT OFFICE.

CYRUS EVERE, OF NEW YORK, N. Y., ASSIGNOR TO LIDGERWOOD MANUFACTURING COMPANY, OF NEW YORK, N. Y., A CORPORATION OF NEW YORK.

LOCKING MEANS FOR OPERATING-LEVERS.

1,205,877.

Specification of Letters Patent.

Patented Nov. 21, 1916.

Application filed June 7, 1913. Serial No. 772,255.

To all whom it may concern:

Be it known that I, CYRUS EVERE, a citizen of the United States, residing at New York city, borough of Brooklyn, county of Kings, 5 and State of New York, have invented certain new and useful Improvements in Locking Means for Operating-Levers, of which the following is a specification.

My invention relates to new and useful 10 improvements in locking means for operating levers, and more particularly contemplates means for preventing simultaneous operation of a plurality or group of operating levers for controlling different parts or 15 mechanisms, or parts of mechanisms, in such a manner that, when one of said levers is operated to control its mechanism, another lever of the group will be automatically locked so that it cannot be manipulated to control 20 its mechanism.

The invention is applicable to all types of machinery, including a plurality of mechanisms, or operations, of such a nature that they should not be controlled or operated 25 simultaneously, in order to insure the operations taking place in proper sequence, or to prevent them from acting counter to each other with disastrous results.

The primary object of the invention is to 30 provide a device of the character set forth which will be extremely efficient and simple in operation, and which will act with certainty in preventing the simultaneous operation of operating levers, or prevent the 35 operation of one lever while another is in position to cause a determined operation of the mechanism controlled thereby.

The invention consists in the improved arrangement and combination of parts to be 40 more fully described hereinafter and the novelty of which will be particularly pointed out and distinctly claimed.

I have fully and clearly illustrated my invention in the accompanying drawings to be 45 taken as a part of this specification, and wherein:

Figure 1 is a perspective view of two operating levers having my invention associated therewith. Fig. 2 is a view in side elevation, partly in section, of the same structure shown in Fig. 1. Fig. 3 is a sectional view through the levers and showing the locking device in plan view, but showing both levers in locked position. Fig. 4 is a 55 detail sectional view through the levers and

showing the locking device in plan view in the position which the parts assume when one lever is being operated to control the determined operation, and the other lever is locked. Fig. 5 is a reduced detail view in 60 plan of a structure embodying my invention.

Before proceeding with the detail description of my invention, I desire to state that the same is not limited to use in any particular combination or mechanism, but is 65 adapted for use in connection with any mechanism, or plurality of mechanisms, where there are operations to be controlled by the operating levers, which should be prevented from taking place simultaneously, 70 and I, therefore, do not describe the invention in connection with any particular type of mechanism.

Referring to the drawings by characters of reference, 1 designates a supporting member, preferably consisting of an I-beam, which serves as a support for the operating levers and the locking means constituting my invention. The upper horizontal flange of this I-beam is provided with a horizontal 80 projection or bracket 2, and with horizontal brackets 3, 3, arranged on opposite sides thereof, and spaced therefrom to form guideways 4, 4, for a purpose to be presently described. Supported on the said upper 85 horizontal flange of the supporting member 1, and spaced apart in vertical parallel relation, are two quadrant frames 5, 5 (see Fig. 5), connected at their upper front and rear ends by spacing pins or bars 6, 6. At their 90 lower forward ends, the quadrant frames have secured therein a horizontally-disposed bearing shaft 7, upon which are fulcrumed two operating levers 8, 8, the fulcrum point being located intermediate the ends of said 95 levers so that they are provided at their lower ends with members 9, 9, projecting below the fulcrum. At 8^a I have shown in dotted lines connections which may connect the levers 8 with the mechanisms or parts 100 they are to control. As shown in the present embodiment of the invention, these operating levers are of the type operated manually by an operator to control the operation of mechanisms or parts thereof. As shown in 105 the drawings, the levers are designed to swing in a vertical plane between the quadrant members 5, 5, and are limited in their swinging movement by the bars 6, 6, which operate as stops to be engaged by said levers 110

at their extreme front and rear positions. The projecting members 9, 9, heretofore described, project downwardly through the guide slots 4, 4, heretofore described, between the brackets 2 and 3.

5 Mounted on the bracket 2, preferably on the upper side thereof, is a locking member, consisting of a plate 10 pivoted on a bolt 11 extending vertically through the bracket 2, secured at its lower end by a nut 12, threaded on the lower end thereof. It will be seen that the pivot bolt 11 for the locking member 10 extends at a right angle to the longitudinal axis of the shaft 7, so that the locking member swings in opposite directions in a plane parallel to the longitudinal axis of the shaft 7 toward one lever or the other. The forward end of this plate, or member, 10, projects beyond the fulcrum 7 of the 15 operating levers, and is provided with lateral projections 13, forming, with the body of the plate, locking shoulders 14 adapted to coöperate with the projections 9, 9, on the operating levers to prevent movement of one 20 of said levers from its forward vertical position accordingly as to whether said locking member is moved to the right or left, as will be presently described.

The ends of the projections 13 are provided with engaging faces 16, 16, which are so located that, when one of the levers is swung on its fulcrum, the member 9 on the lever engages the adjacent engaging face to positively hold the locking member in locking engagement with the opposite lever. The faces 16, 16, and the members 9, 9, are so proportioned that, when the locking member is operated by one of the levers, the member 9 thereon will be in constant engagement with the adjacent face 16 throughout the entire movement of the lever until it is returned to vertical position. This assures one lever being positively locked throughout the swinging movement of the other lever.

45 The operation of the invention is as follows: Assuming that both operating levers 8 are in forward substantially vertical position, and that the plate 10 is in substantially the position shown in Fig. 3, in which the projections 9 on the lower ends of the operating levers are both in rear of the locking shoulders 14. If then one of the levers is grasped by the operator and pulled to the 50 rear, say, the left-hand lever, as shown in the figures, the projection 9, carried by said lever, will strike against the shoulder 14 and swing the locking plate 10 to the right so that the locking shoulder on the right-hand side of the plate will be pushed in front of the projection 9 on the operating lever which is not to be moved. By continued movement of the lever which is being 55 swung to the rear, the projection 9 thereon 60 will ride off the shoulder 14 and will engage

with its side face the face 16 of the projection 13, thereby positively holding the locking plate in position to lock the right-hand lever against movement as long as the left-hand lever is out of vertical position. When 70 the lever, which has been swung to the rear, is returned to its normal vertical position, the projection 9 thereon returns to its normal position in rear of the shoulder 14, on that side of the locking plate, so that the 75 said plate is free to be swung out of engagement with the other lever, should it be moved. Upon swinging the right-hand lever to the rear, the projection 9 thereon coöperates with the locking plate to operate the 80 same in the manner above described to lock the left-hand lever against being operated.

The side faces 16 of member 10 preferably flare toward the free end of said member, as clearly shown in Figs. 3 and 4, so that the 85 face engaged by one of the levers to shift said member to lock the other lever will be parallel to the face of the first-named lever. This is desirable so that there will be an extended bearing face between the parts and 90 no sharp projections which would cause objectionable wear.

What I claim and desire to secure by Letters Patent of the United States is:—

1. In combination, a pair of operating 95 levers movable in vertical planes, a locking member mounted on a vertical pivot between said levers and movable in opposite directions toward and away from said levers respectively, locking shoulders on said member on opposite sides thereof to coöperate with the respective levers, and means whereby the swinging movement of either lever moves said locking member toward the other lever to cause one of said shoulders to lock 100 said other lever against movement.

2. In combination, a pair of operating levers, each having a member extending below the fulcrum thereof, a locking device pivoted between said members to swing in 110 a direction lengthwise of the fulcrum, a projection on each side of said locking device adapted to coöperate with the said member adjacent thereto to lock the lever carrying said member against movement, and means 115 whereby the swinging movement of one lever moves the device laterally to cause it to lock the other lever throughout said swinging movement.

3. In combination, a pair of operating levers, each having a member projecting below the fulcrum thereof, a locking plate pivoted between said members and having lateral projections on opposite sides thereof 125 forming shoulders to coöperate with said members to lock the levers against movement, said members on the levers and the projections on the locking plate being so arranged that the swinging movement of one lever engages the projection adjacent thereto 130

to move the locking plate toward the other lever to place the locking shoulder for said other lever in locking engagement therewith.

- 5 4. In combination, a pair of operating levers fulcrumed on the same axis, a locking plate pivoted between said levers and movable in opposite directions in a plane parallel with said axis, said plate having
10 lateral projections on opposite sides thereof forming shoulders to coöperate with said levers to lock the levers against movement, and an engaging face on each projection

adapted to be engaged by the adjacent lever when swung on its fulcrum to hold the plate 15 in locking engagement with the other lever throughout the swinging movement of said first-named lever.

In testimony whereof I have hereunto signed my name in the presence of two sub- 20 scribing witnesses.

CYRUS EVERS.
